UNITED STATES PATENT OFFICE.

BENJAMIN LIPPER AND ALFRED A. COURTS, OF PHILADELPHIA, PENNSYLVANIA, ASSIGNORS TO AUGUSTUS A. LAZARUS, ISAAC A. SCHWARZ, AND BENJAMIN LIPPER, OF SAME PLACE.

DESIGN FOR A DRESS-TRIMMING.

SPECIFICATION forming part of Design No. 21,341, dated February 16, 1892.

Application filed January 19, 1892. Serial No. 418,585. Term of patent 3½ years.

To all whom it may concern:

Be it known that we, BENJAMIN LIPPER and ALFRED A. COURTS, citizens of the United States, and residents of Philadelphia, Pennsylvania, have invented a Design for a Dress-Trimming, of which the following is a specification.

Our design is fully shown in the accompanying drawing, which represents a face view of a piece of the trimming.

The design comprises the central tape-like band or ribbon *a*, adjacent to each edge of which is a narrow band *b*, and projecting beyond these bands are fan-like figures *d*, formed by cord loops of different lengths, and on the face of the band at the base of each of the fan-like figures is a loop *f*, cords *g* extending diagonally across the tape or ribbon *a* from

one loop to the other. The fan-like figures *d* are separated from each other, the edging beyond the bands *b* in the spaces between said figures *d* consisting, simply, of short loops of uniform length.

We claim—

The design for a dress-trimming, substantially as described, and as shown in the accompanying drawing.

In testimony whereof we have signed our names to this specification in the presence of two subscribing witnesses.

BENJAMIN LIPPER.
ALFRED A. COURTS.
